CLAIM

The ornamental design for a display screen or portion thereof with animated graphical user interface, as shown and described.

DESCRIPTION

FIG. 1 is a first image of a first embodiment of a display screen or portion thereof with animated graphical user interface, showing my new design;

FIG. 2 is a second image thereof;

FIG. 3 is a third image thereof;

FIG. 4 is a fourth image thereof;

FIG. 5 is a fifth image thereof;

FIG. 6 is a first image of a second embodiment of the display screen or portion thereof with animated graphical user interface;

FIG. 7 is a second image thereof;

FIG. 8 is a third image thereof;

FIG. 9 is a fourth image thereof; and,

FIG. 10 is, a fifth image thereof.

The broken lines in the figures show a display screen or portion thereof, or an electronic device having a display screen, and form no part of the claimed design.

The appearance of the animated image sequentially transitions between the images shown in FIGS. 1-4 and FIG. 5-8 respectively. The process or period in which one image transitions to another forms no part of the claimed design.
